J. G. EVANS

COMBINED ROAD MARKER AND MAIL BOX SUPPORT

Filed June 11, 1923

UNITED STATES PATENT OFFICE.

JEWETT G. EVANS, OF FORT WORTH, TEXAS.

COMBINED ROAD MARKER AND MAIL-BOX SUPPORT.

Application filed June 11, 1923. Serial No. 644,620.

My invention relates to combined road markers and mail boxes; and the object is to provide mail boxes which will protect mail against weather conditions and depre-
5 dations and which will support the mail boxes in positions convenient for the mail carrier and for the owners and to adapt the apparatus for a road marker and also for a mail route marker. Other objects and ad-
10 vantages will be fully explained in the following description and the invention will be more particularly pointed out in the claims.

Reference is had to the accompanying drawings which form a part of this application.

Fig. 1 is a front elevation of the apparatus. Fig. 2 is a side or edge elevation of the same.

Similar characters of reference are used to indicate the same parts throughout the several views.

The apparatus includes an upright frame which is provided with posts 1, 2, and 3. These posts may be set in the ground or cement or otherwise. The post 2 extends up to a frame piece 4 which is attached thereto. The frame piece 4 is also attached to the posts 1, 2 and 3. An ornamental lattice member 5 may be attached to the posts 1, 2, and 3. A board 6 may be mounted on the frame member 4 and attached to the posts 1 and 3 for use in displaying information for the benefit of travelers. A frame member 7 is attached to the board 6 and is supported on the posts 1 and 3. Upright frame members 8 are attached to the posts 1 and 3 and to frame member 7. Upright frame members 9 are attached to the frame mem-
30 ber 7 and an angular roof member 10 is attached to the uprights 8 and 9 for protecting the mail boxes 12 which are attached to the frame member 7. The mail boxes 12 may be of any suitable type. The mail boxes may be protected on the back side by a screen 13. End members 14 are connected to the screen 13 and to the frame members 8 and the screen members should extend the whole distance between the supporting frame mem-
45 ber 7 and the roof 10. This space between the frame 7 and the roof 10 is made deep enough to contain packages which may be

mounted on the mail boxes. The slanting sides of the roof 10 may be utilized for furnishing information to the public or travel-
ers.

The device shown will be securely supported by the frame members provided and a display board is provided in a conspicuous place for furnishing information to travelers in the manner illustrated. The same frame members support a receptacle or compartment for mounting mail boxes and the roof protects the mail boxes and other mail matter generally from rain and snow. Ample provision is made in the compartment for mail boxes to contain packages too large for the mail boxes.

What I claim is, —

1. A combined road marker and mail box support comprising a central post and end posts, bracing lattice members attached to said posts, an information-carrying board mounted and attached to said posts, a mail box compartment mounted on said board and attached thereto and to said end posts, a roof provided with members for carrying information and for protecting said mail box compartment from weather conditions, and wire screen attached to the rear side of said mail box compartment and roof for protecting packages of mail placed on top of the mail boxes.

2. A combined road marker and mail box support comprising a central post and end posts extending higher than said central post, an information carrying board or plate mounted on said central post and attached to said end posts, a mail box support for a plurality of mail boxes mounted on and attached to said end posts and to said information carrying board, braces for said supporting board and said end posts, a roof mounted on the tops of said end posts at a relatively high position above said support and a wire screen attached to said end posts and to the rear sides of said support and roof and forming a relatively large compartment for mail boxes and other mail matter too large for mail boxes.

In testimony whereof, I set my hand this 5th day of June, 1923.

JEWETT G. EVANS.
